ISAIAH SHAW, OF FOUR CORNERS, MARYLAND.

Letters Patent No. 88,088, dated March 23, 1869.

IMPROVEMENT IN POTATO-DIGGERS.

The Schedule referred to in these Letters Patent and making part of the same.

Be it known that I, ISAIAH SHAW, of Four Corners, Montgomery county, Maryland, have invented a new and improved Potato-Digger and Plow combined; and I do hereby declare that the following is a full, clear, and exact description thereof, reference being had to the accompanying drawings, in which—

Figure 1 is a perspective view of my combined potato-digger and plow.

My invention consists in so constructing a potato-digger or plow that all liability to choking at the throat is obviated.

My invention further consists in so constructing the frame that it may be used as a potato-digger or plow of any kind.

My invention further consists in the employment of a brace, of a peculiar construction, to strengthen the plow.

My invention further consists in the employment of certain devices applicable to potato-diggers, hereinafter more fully set forth.

In the accompanying drawing—

The front portion *a*, of the beam, is made straight. From a point of the beam, about over the share, the beam is made to curve, as seen at *a'*, until it meets the shoe *b*, to which it is securely fastened.

The beam is again bent from the point where it is at first attached to the shoe *b*, as seen at *a''*, and is again attached to the shoe at the point *o*.

The share is attached to the front part of the beam *a* by screws *e e*, or in any other suitable manner.

In the ordinary plow, it is well known that dirt, grass, weeds, &c., accumulate rapidly at the throat, or between the beam and the lower part of the plow, requiring frequent stoppages of the plow, to remove the filth at the throat.

By my construction of plow, the choking above described is avoided, as the grass or weeds would pass into the open space in the beam, and if such grass, &c., did not, as it usually would, readily pass off the plow, the plowman could, by placing his foot upon it, remove it from the plow without the necessity of stopping it.

A roller might also be employed at the curve of the beam, at the point *a''*, to remove any grass, &c., which might accumulate there, or a wheel might be employed, running on the ground opposite the point *a''* of the beam, which, by pressing on any grass which might accumulate at the point *a''*, would effectually remove it from the plow.

I have found, however, in practice, that in my construction of beam, little or no choking is experienced, and if any grass accumulates at the point *a''*, it can be easily removed by the plowman stepping upon it, without the necessity of stopping the plow.

c is a brace attached to the front part of the beam,

at the point *d*. From thence it passes around the beam, concentric with it, and is attached to the rear portion of the shoe at *m*.

d d are pillars or pieces connecting the brace *c* with the beam; by this connection of brace I obtain almost if not as much strength as if the whole beam was made of the thickness of the brace and beam combined, while greater lightness, a necessary requisite in a plow, is attained.

h h are the handles, which may be adjusted by a pin and holes, such as are ordinarily used.

In the drawing—

S is the share of a potato-digger, though it is obvious that a shingle shovel or any other share, might be used.

ff are wings attached on each side of the share. These wings can be adjusted laterally, by means of a pin and holes *n n*, to adapt the digger to the width of furrow.

ll are arms, connected together at their bases, and loosely attached by a nut and screw, or otherwise, at *i*, to the shoe *b*. The arms *ll* are intended to raise the potatoes above the dirt, &c., to separate them therefrom, and hence the pieces *ll* are attached loosely to the shoe, so that from the motion of the plow, they may have a vibratory motion to some extent.

The beam may be made in one or several pieces.

The operation of my potato-digger is as follows:

The wings *ff* are adjusted to adapt them to the width of furrow, the dirt and potatoes pass between the wings *ff* and the beam, and are separated by the projections *ll*, which have a vibratory movement from the forward movement of the plow, they being loosely attached to the shoe.

Having thus fully described my invention,

What I claim as new, and desire to secure by Letters Patent, is—

1. A plow-beam, *a a' a''*, constructed substantially as described.
2. The combination of the plow-beam *a a' a''*, constructed as described, with the shoe *b*.
3. The combination of the beam *a a' a''*, brace *c*, pillars *d d*, and shoe *b*.
4. The adjustable wings *ff*, in combination with share *S*, substantially as described.
5. The projecting pieces *ll*, loosely attached to the shoe *b*, as and for the purpose set forth.
6. The combination of the share *S*, adjustable-wings *ff*, and projecting-pieces *ll*, substantially as described.
7. The combination of the beam *a a' a''*, shoe *b*, share *S*, adjustable-wings *ff*, and projecting-pieces *ll*, substantially as described.

ISAIAH SHAW.
